(57) CLAIM

The ornamental design for a tampon wrapper, as shown and described.

DESCRIPTION

FIG. 1 is a front perspective view of the tampon wrapper showing our new design;

FIG. 2 is a back perspective view thereof;

FIG. 3 is a front view thereof;

FIG. 4 is a back view thereof;

FIG. 5 is a left side view thereof;

FIG. 6 is a right-side view thereof;

FIG. 7 is a top view thereof; and,

FIG. 8 is a bottom view thereof.

The broken line showing portions of the tampon wrapper is included for the purpose of illustrating environmental structure and forms no part of the claimed design.
